CLAIM

The ornamental design for a vehicle muffler, as shown and described.

DESCRIPTION

FIG. 1 is a front elevational view of a vehicle muffler illustrating the present design;

FIG. 2 is a right side elevational view of the vehicle muffler shown in FIG. 1;

FIG. 3 is a rear elevational view of the vehicle muffler shown in FIG. 1;

FIG. 4 is a left side elevational view of the vehicle muffler shown in FIG. 1;

FIG. 5 is a top plan view of the vehicle muffler shown in FIG. 1;

FIG. 6 is a bottom plan view of the vehicle muffler shown in FIG. 1;

FIG. 7 is a front isometric view of the vehicle muffler shown in FIG. 1;

FIG. 8 is a rear isometric view of the vehicle muffler shown in FIG. 1; and,

FIG. 9 is a front isometric view of the vehicle muffler shown in FIG. 1 in a typical environment.

The broken line showing in FIG. 9 is for environmental purposes only and forms no part of the claimed design.
